PISTON VALVE

William S. Jensen, Chico, Calif.

Application January 21, 1933. Serial No. 652,831

3 Claims. (Cl. 123—188)

This invention relates to the valve mechanisms of gas engines, my principal objects being to provide a valve arrangement and an operating means therefor so constructed that the usual tappets and accompanying parts such as springs, push rods, adjusting nuts etc. are eliminated; there is no possibility of these valves being burned out, they never need adjustment, are perfectly silent in operation and their tightness or compression is improved rather than lessened with use and no regrinding or other reconditioning treatment is ever necessary. Also my improved valves may be operated with but little strain on the timing gears and the valve controlling shaft driven thereby and the sudden shocks imparted to the gears and shaft incident to the operation of the usual cam shaft are avoided.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a transverse section of a gas engine equipped with my improved valve structure showing the exhaust valve open.

Fig. 2 is a similar view showing the position of the valve parts as the intake valve is about to open.

Fig. 3 is a longitudinal section of a valve unit showing the valve fully open.

Fig. 4 is a similar view showing the valve fully closed.

Fig. 5 is a fragmentary sectional plan taken on the line 5—5 of Fig. 1.

Fig. 6 is a bottom plan view of a valve unit detached.

Referring now more particularly to the characters of reference on the drawings, the engine comprises a cylinder 1 having a piston 2 slidable therein and connected by a rod 3 with the main crank shaft 4 in the usual manner.

Disposed to one side of the cylinder and formed with the cylinder block are intake and exhaust valve chambers 5 and 6, there being one pair of these chambers for each cylinder and being spaced lengthwise of the engine in side by side relation. A single lateral passage 7 connects both chambers with the adjacent side of the cylinder just above the topmost position of the piston. The valve chambers are of relatively long cylin-

drical form open on both ends and extending both above and below the passage 7, and being thus partly formed in the removable cylinder head 8.

Separate intake and exhaust valve units indicated generally as I and E respectively are mounted in the chambers 5 and 6, and since these units are duplicates of each other it will be sufficient to describe only one of the same in detail. Each intake valve unit for instance comprises concentric outer and inner sleeves 9 and 10 respectively spaced apart. They are connected as a unit and closed on their crank case ends by a head 11. This is engaged by the adjacent end of a connecting rod 12 whose lower end engages a crank 13 on a crank shaft 14. This crank shaft is disposed to one side of the main crank shaft 4 and is driven at one-half the speed of the same by gearing 15. The sleeves 9 and 10 have aligned ports 16 positioned to align with the passage 7 when the valve unit is at the topmost point of its stroke. Each exhaust valve unit is similarly operated by a connecting rod 12a engaging another crank 13a on the crank shaft 14 and which is circumferentially offset from the intake crank 13 when the valves will operate the proper amount so that the valves will operate in the proper timed relation to the strokes of the piston as usual.

Another sleeve 17 is slidably engaged by and projects between the sleeves 9 and 10 from above, having a top flange 18 supported on top of the cylinder head. The sleeve 17 is freely open on both ends and its length is such that when the movable sleeve unit is at the top of its stroke the bottom of the sleeve 17 is very near the head 11 as shown in Fig. 3. This gives a large bearing area between the various sleeves with all positions of the same and thus insures good compression or gas holding ability.

The sleeve 17 also has a port 19 intermediate its ends, the same size as the ports 16 and in permanent alignment with the passage 7. A supply of lubricant for the valve chambers and for the contacting surfaces of the various sleeves is obtained by splash from the crank case. The head 11 has vertical oil passages 20 between the plane of the sleeves 9 and 10 so that oil vapor may work into the space above the head and between the sleeves. Intake and exhaust manifolds 21 and 22 are secured to the cylinder head over the flanges 18 of the corresponding sleeves 17, thus holding said sleeves in place, said manifolds establishing communication between the parts connected thereto and the interior of the valve units.

The operation of the valve structure will be

self-evident, the ports of each valve only being completely alined with each other and with the cylinder passage once for every four strokes of the piston as is required in the operation of the 5 usual four-cycle engine. The stroke of the crank shaft 14 and consequently that of the valve sleeves is relatively long so that the valves will be partially opened for at least a full stroke of the piston as is required for efficient operation. This 10 also permits of the use of large ports and correspondingly efficient scavenging and suctional action.

Compression rings 23 are disposed about the sleeves 9 adjacent their lower ends, to prevent 15 possible oil pumping and gas leakage past said ends, which are relatively cool compared to the upper ends of the sleeves, and hence do not expand so much to give the necessary pressure tight fit when in use.

20 From the foregoing description it will be readily seen that I have produced such a device as substantially fulfills the objects of the invention as set forth herein.

25 While this specification sets forth in detail the present and preferred construction of the device, still in practice such deviations from such detail may be resorted to as do not form a departure from the spirit of the invention, as defined by the appended claims.

30 Having thus described my invention what I claim as new and useful and desire to secure by Letters Patent is:

1. In an internal combustion engine having a cylinder, a control valve structure comprising a
35

valve chamber extending lengthwise of the cylinder to one side of the same, there being a passage between the chamber and cylinder, a fixed sleeve depending into the chamber in spaced relation to the walls thereof and having a port alined with said passage, a conduit for gas connected to the outer end of the sleeve, a pair of sleeves slidably engaging and between which the fixed sleeve projects, said pair of sleeves having alined ports to aline with the fixed valve port when said pair of sleeves occupy a certain position, and means applied to said pair of sleeves to reciprocate the same simultaneously.

2. In an internal combustion engine having a cylinder, a control valve structure comprising a 90 valve chamber extending lengthwise of the cylinder to one side of the same, there being a passage between the chamber and cylinder, a fixed sleeve depending into the chamber in spaced relation to the walls thereof and having a port alined with said passage, a conduit for gas connected to the outer end of the sleeve, a pair of sleeves slidably engaging and between which the fixed sleeve projects, said pair of sleeves having alined ports to aline with the fixed valve port when said pair 100 of sleeves occupy a certain position, a head closing and connecting the pair of sleeves as a unit at the end thereof opposite the conduit, and means applied to the head to reciprocate the same.

3. A structure as in claim 2, in which the head, 105 between the pair of sleeves, is provided with oil passages therethrough.
